(57) **CLAIM**

We claim the ornamental design for a machine for grinding vegetation, as shown and described.

DESCRIPTION

FIG. 1 is a front view of a machine for grinding vegetation showing our new design.

FIG. 2 is a rear view thereof.

FIG. 3 is a right side view thereof.

FIG. 4 is a left side view thereof.

FIG. 5 is a top plan view thereof.

FIG. 6 is a bottom view thereof.

FIG. 7 is a high-angle front view thereof.

FIG. 8 is a high-angle front-right side view thereof.

FIG. 9 is a high-angle front-left side view thereof.

FIG. 10 is a high-angle rear-left view thereof; and,

FIG. 11 is a high angle front-left side view thereof.
